(57) **CLAIM**

The ornamental design for a handle for combined knife and fork, as shown and described.

DESCRIPTION

FIG. 1 is a first perspective view of a handle for combined knife and fork, showing my new design;
FIG. 2 is a second perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a third perspective view thereof, shown with the fork in assembled condition;
FIG. 10 is a fourth perspective view thereof, shown without the fork for ease of illustration; and,
FIG. 11 is an exploded view thereof, shown in reduced scale. The broken lines in the drawings depict portions of the handle for combined knife and fork that form no part of the claimed design.

1 Claim, 11 Drawing Sheets
